US00D599242S

(12) **United States Design Patent**
Yang

(10) **Patent No.:** **US D599,242 S**
(45) **Date of Patent:** **** Sep. 1, 2009**

(54) **ELECTRONIC ARTICLE SURVEILLANCE TAG**

(75) Inventor: **Xiao Hui Yang**, Los Altos, CA (US)

(73) Assignee: **WG Security Products**, San Jose, CA (US)

(**) Term: **14 Years**

(21) Appl. No.: **29/332,707**

(22) Filed: **Feb. 23, 2009**

(51) **LOC (9) Cl.** **10-05**

(52) **U.S. Cl.** **D10/104**

(58) **Field of Classification Search** **D10/104, D10/106; 340/571.2, 571.8, 571.9, 571.1, 340/572.8; 24/704.1; 70/57.1; 135/16; D8/332, D8/333, 342, 343**

See application file for complete search history.

(57) **CLAIM**

The ornamental design for an electronic article surveillance tag, as shown and described.

DESCRIPTION

FIG. 1 is a front perspective view of my new design for a lanyard tag.

FIG. 2 is a front view of my new design for a lanyard tag.

FIG. 3 is a back view of my new design for a lanyard tag.

FIG. 4 is a left side view of my new design for a lanyard tag.

FIG. 5 is a right side view of my new design for a lanyard tag.

FIG. 6 is a top view of my new design for a lanyard tag; and,

FIG. 7 is a bottom view of my new design for a lanyard tag.

1 Claim, 5 Drawing Sheets

FIG. 1

FIG. 2

FIG. 3

FIG. 4

FIG. 5

FIG. 6

FIG. 7
